P. E. GERHARD

RAILROAD SWITCH HEEL BLOCK STRUCTURE

Filed March 25, 1926

UNITED STATES PATENT OFFICE.

PAUL EUGENE GERHARD, OF LEBANON, PENNSYLVANIA, ASSIGNEE TO LEBANON STEEL FOUNDRY, OF LEBANON, PENNSYLVANIA, A CORPORATION OF PENNSYLVANIA.

RAILROAD-SWITCH HEEL-BLOCK STRUCTURE.

Application filed March 25, 1926. Serial No. 97,162.

This invention relates to a railroad switch and heel block structure. Its object is to strengthen and to increase the durability and safety of a working assemblage of a main track rail, a switch rail section or sections and an interposed heel block.

In the accompanying drawings forming a part hereof and illustrating my invention,

Fig. 1 is a top plan view of a railroad switch and heel block structure embodying this invention.

Fig. 2 is a perspective view of my new heel block, top-side down and shows the construction of the under side of the heel block.

Fig. 3 is an end elevation with the track and switch rails in transverse cross section at line 3-3 of Fig. 1 and shows my new heel block in a working assemblage.

In the drawings, heel block A is a chambered steel casting open on its under side. The block, in use, is located, as heretofore, between main rail B and a stationary switch rail section D, and a switch point rail D'.

The rail B, stationary section D and interposed heel block A are rigidly connected together horizontally by bolts E severally provided with a nut, the bolts passing through the rail webs and the side walls of the heel block. The heel block sides taper in the direction of the free end of the switch point rail.

My new heel block is a chambered, steel casting open on its under side and formed with a roof wall 1 which is preferably imperforate, the roof wall being between upwardly projecting, lengthwise extending, corner marginal walls 2. The block is cast with side walls 3 provided, along their

length, with opposed, spaced apart, bolt holes 4; with end walls 5 and dependent from the roof wall and between the sides 3, with a series of transverse, spaced apart, vertical webs 6. The end walls and webs

have the same contours and dimensions. The under edges of the end walls and webs are preferably upwardly recessed between their ends for diminution of weight. The under edge ends of the end walls and webs, along each side of the casting, slant upwardly and outwardly at 7 to form discontinuous bearings for a rail base flange a. These bearings 7 are in alinement one with another and severally merge with the under, lengthwise

straight, upwardly and outwardly slanting, 55 under edge walls 8 of the sides 3. The edge walls 8 form continuous bearings for opposed rail base flanges a on which they, as well as the bearings 7 rest when in assemblage. The side walls 3 and rail margins 2 taper 60 from the butt end of the block in the direction of the switch point rail section. The roof wall is depressed between the upwardly projecting margins 2 to accommodate wheel flanges extending below the rail heads. 65 The upper corner margins 2 are of equal height from the bearing surfaces at 7 and 8 and are so dimensioned,—relatively to the dimension of the main rail, the switch rail section and the switch point rail, between 70 the upper surface a of each said base flange with which the block contacts, and the thereabove, under, overhanging surface a' of a rail head, as to leave a clearance at x between the margins 2 and the opposed rail 75 head surfaces.

Thus the rail block bearings 7 and 8 rest on and bear against their opposed rail base flanges, out of contact with the overhanging surfaces of the rail heads.

The outside surfaces of the block sides 3 are shaped and dimensioned to fit and bear against a rail web 9, along each side of the block. In the working assemblage, the block sides are clamped against the rail webs, 85 forming a transverse, strain resisting structure in which the under, lengthwise edges of the block are clamped downwardly against the opposed rail base flanges by the clamp bolts, the clearance at x preventing 90 any upward thrust of the block against overhanging portions of the rail head.

As herein shown, the main rail, the switch rail section, the switch point rail at its butt end portion, and the interposed heel block 95 are all rigidly clamped together. This is in accordance with the practice of some railroads when the switch point rail is of considerable length. A different and well known practice is to clamp the main rail and the heel block rigidly together and to hold the butt end of the switch point rail in a relatively loose relation to that end portion of the interposed heel block which is laterally opposed to the butt end portion 100 of the switch point rail.

Advantages of the present invention are:
My relatively light weight, cast steel heel

blocks are practically free from liability to transverse fracture in consequence of the wave motion of the rails and variations in solidity of the road bed. The clearances 5 at α not only to relieve the overhanging rail head portions of upward and outwardly acting thrusts, but, as the clearances are due to the reduced dimension of the height of the block, make the blocks adapted for location 10 between rail base flanges and head flanges notwithstanding variations in cross sectional rail contour. The long sides of my new blocks being in direct contact with the rail webs strongly stiffen and support 15 the webs, making a laterally stiffer and safer switch structure. The distribution of the separated, slanted bearing surfaces 7, relieves the heel block, to an important extent, from transverse strains arising in consequence 20 of rail wave motions and variations in roadbed solidity.

Heel blocks have heretofore been made of solid cast iron transversely provided with bolt holes drilled through the solid blocks. 25 This involved undue labor and expense. In my new block, the bolt holes are cored in the casting, whereby all machine work in relation to the formation of the bolt holes is eliminated. Such older cast iron blocks 30 were made with frequent openings from top to bottom for reduction of weight. Such vertical openings received water and snow, and mud formed in them, whereby the walls of the holes were subjected to undesirable 35 oxidation. Under freezing conditions, these vertical holes are apt to become filled with ice which, expanding, tends to crack the blocks and frequently does so. It is for such reason that the roof wall is preferably 40 imperforate, as shown.

The upward and outwardly slanted bearing surfaces 7 and 8 are slanted to match and fit the upwardly and inwardly slanting, upward surfaces α of the rail base flanges at 45 each side of a rail web; and the bolt holes through the rail webs and through the heel block sides are so located and the bolt shanks are so dimensioned that when the members are bolted together, the bearings 7 and 8 are 50 held downwardly and clampingly against the rail base flanges whereby the upper, lengthwise extending, marginal walls 2 are kept out of contact with the rail heads.

What I claim is:

55 1. In a railway switch and heel block structure, the combination of a main rail; a stationary switch rail section; a switch point rail and a chambered heel block open on its under side; the heel block having long side 60 walls one of which is partially opposed to the web and a base flange of the stationary switch rail section and also partially opposed to the web and a base flange of the switch point rail and the other of which is 65 opposed lengthwise to the main rail web

and base flange; one side wall of the heel block bearing against the main rail web and its adjacent base flange and its other side wall bearing against the web and a base flange of the stationary switch rail; the opposite, under, lengthwise extending edges 70 of the side walls of the heel block being provided with bearing surfaces bearing on the rail base flanges; the webs of the main, stationary and switch point rails being 75 formed with bolt holes and the heel block side walls being formed with transversely alined bolt holes registering with the bolt holes through said webs; and clamp bolts through the bolt holes in the web and block sides, effective to clamp the heel block side walls to the main and stationary switch rail and operative to connect the block sides with the web of the switch point rail and to hold the under edge, bearing surfaces of the heel block 80 against rail base flanges, with the upper, lengthwise, marginal walls of the heel block 85 out of contact with the rail heads.

2. In a railway switch and heel block structure, the combination of a main rail; a stationary switch rail section; a switch point rail and a chambered heel block open on its under side; the heel block having long side walls one of which is partially opposed to the web and a base flange of the stationary switch rail section and also partially opposed to the web and a base flange of the switch point rail and the other of which is 90 opposed lengthwise to the main rail web and base flange; one side wall of the heel block bearing against the main rail web and its adjacent base flange and its other side wall bearing against the web and a base flange of the stationary switch rail; the opposite, under, lengthwise extending edges 95 of the side walls of the heel block being provided with bearing surfaces bearing on the rail base flanges; the webs of the main, stationary and switch point rails being formed with bolt holes and the heel block side walls being formed with transversely alined bolt holes registering with the bolt holes through said webs; and clamp bolts through the bolt holes in the web and block sides, effective to clamp the heel block side walls to the main and stationary switch rail and operative to connect the block sides with the web of the switch point rail and to hold the under edge, bearing surfaces of the heel block 100 against rail base flanges, with the upper, lengthwise, marginal walls of the heel block 105 out of contact with the rail heads.

3. In a railway switch and heel block structure, the combination of a main rail; a 110

stationary switch rail section; a switch point rail and a chambered heel block open on its under side; the heel block having long side walls one of which is partially opposed to the web and a base flange of the stationary switch rail section and also partially opposed to the web and a base flange of the switch point rail and the other of which is opposed lengthwise to the main rail web and base flange; one side wall of the heel block bearing against the main rail web and its adjacent base flange and its other side wall bearing against the web and a base flange of the stationary switch rail; the opposite, under, lengthwise extending edges of the side walls of the heel block being provided with bearing surfaces bearing on the rail base flanges; the webs of the main, stationary and switch point rails being formed with bolt holes and the heel block side walls being formed with transversely alined bolt holes registering with the bolt holes through said webs; and clamp bolts through the bolt holes in the web and block sides, effective to clamp the heel block side walls to the main and stationary switch rail and operative to connect the block sides with the web of the switch point rail and to hold the under edge, bearing surfaces of the heel block against rail base flanges, with the upper, lengthwise, marginal walls of the heel block out of contact with the rail heads; said chambered heel block being provided with integral end walls and between the end walls with integral, transverse, spaced apart webs in a dependent series, said webs severally having, at their under corner portions, bearing surfaces resting on the rail flanges; such bearing surfaces severally merging with an under edge of a side wall of the block, and the under edge of each side wall forming a continuous bearing resting on a rail base flange; the chambered heel block being formed with an imperforate roof wall having lengthwise extending margins projecting above the roof wall.

5. For railway switches, a chambered, cast steel heel block open on its under side and formed with an imperforate roof wall; lengthwise extending, opposite marginal walls projecting above the roof wall; opposite, lengthwise extending side walls; end walls; and, between the end walls, with a series of spaced apart, transverse webs; the under outward end portions of the end walls and webs merging into side wall, under edges; the end portions of the end walls and said under edges, some at one side and others at the other side of the block chamber, slanting upwardly and outwardly and forming, at each side of the chamber, a lengthwise extending series of rail base flange bearings.

Signed at Lebanon in the county of Lebanon and State of Pennsylvania this 18th day of March, A. D. 1926.

PAUL EUGENE GERHARD.
